UNITED STATES PATENT OFFICE.

MAYNARD D. CHURCH, OF HARTFORD, CONNECTICUT, ASSIGNOR TO THE TERRY STEAM TURBINE COMPANY, OF HARTFORD, CONNECTICUT, A CORPORATION OF CONNECTICUT.

STEAM TURBINE.

Application filed October 17, 1921. Serial No. 502,180.

To all whom it may concern:

Be it known that I, MAYNARD D. CHURCH, a citizen of the United States, residing at Hartford, in the county of Hartford and 5 State of Connecticut, have invented a new and useful Improvement in Steam Turbines, of which the following is a specification.

This invention relates to multiple stage steam turbines of the class known as mixed pressure and bleeder turbines. In multiple stage turbines it is frequently desirable to take out or put in at one of the intermediate stages steam at a pressure less than the pressure in the intake steam ring and 10 greater than the pressure in the exhaust opening. For the best results, the stage at which this steam is removed or added must be chosen with reference to the pressure conditions in the various stages. Previously 15 it has been customary to provide casings constructed with particular reference to the stage selected for adding or removing the steam.

The object of the present invention is to 20 provide a standard casing so designed and with the internal and active members so arranged that the turbine may be set up to operate, if desired, without taking out or adding steam, or the elements can be 25 so assembled that steam may be taken out or added at any one of several stages in order that the desired bleeder or mixed pressure result may be attained most efficiently.

This object is accomplished by designing 30 the turbine casing with an intermediate pressure or bleeder chamber or chambers and forming an opening or openings the length of several of the intermediate stages, 35 through the wall of the diaphragm and rotor chamber to this auxiliary chamber, which opening or openings may be completely shut off by the rims of the stationary nozzle diaphragms or any portion of 40 the opening or openings may be left exposed by omitting or so disposing the diaphragms as to leave a space between the diaphragms and rotors, at the stage selected 45 to take off or add the steam.

50 Figure 1 of the accompanying drawings shows a vertical section of a multiple stage turbine constructed according to this in-

vention with a full complement of diaphragms and rotors. Fig. 2 shows a longitudinal section of a portion of the turbine 55 with some of the intermediate stage diaphragms and rotors omitted to provide a space between two diaphragms, as when the machine is built to be used as a mixed pressure or bleeder turbine. Fig. 3 shows a 60 longitudinal section of a portion of the casing with the diaphragms and rotors so arranged and the connections so made that steam may be wholly or partly shut off from the stages below the stage at which the turbine is bled. Fig. 4 shows a transverse section on smaller scale of the casing taken on the line 4-4 on Fig. 2. Fig. 5 shows a 65 transverse section of the casing on the plane indicated by the dotted line 5-5 on Fig. 3. 70

Bleeder and mixed pressure turbines are 75 essentially alike in construction, the former involves taking out and the latter putting in an available quantity of low pressure steam at an intermediate stage. In some cases it is desirable to bleed at one stage and put back that which is not required to keep the bleeding pressure constant, at a lower stage. This invention contemplates a construction which may be readily arranged to 80 meet any of these conditions.

The casings of these turbines are 85 commonly made with a lower section 1 and an upper section 2 securely bolted together. At one end of the casing is an intake-head 3 and at the other end is an exhaust-head 4. The intake-head has an annular steam chamber 5 that is adapted to be connected with the high pressure supply of steam and the exhaust-head has an opening 6 that 90 is usually connected with a condenser.

The shaft 7 extends through suitably packed bearings 8 and 9 in the heads. Secured to the shaft at intervals are the several rotor wheels 10 having buckets 11 95 of the required capacity. Located between the rotors but with their rims closely fitted together and to the cylindrical bore of the casing are the stationary diaphragms 12 having nozzles 13. Steam is admitted at 100 high pressure from the annular steam chamber through the nozzles 14 to the high pressure rotor wheels, and thence with varying pressure from stage to stage it passes

through the nozzles of the several diaphragms and buckets of the rotors to the exhaust through which it escapes at low pressure.

5 In the lower section of the casing is a chamber 15 and through the cylindrical wall of the diaphragm and rotor chamber to this auxiliary chamber is an opening 16 that in the form shown is bridged by longitudinal ribs 17. This opening is made of such length that it spans the width of several of the intermediate stage diaphragms and rotors, and the chamber has an external opening 18 that is designed to 10 be provided with a fitting or pipe connection 19, through which available steam from any external source may be admitted to the chamber or through which desired steam may be taken from the chamber for any 15 outside use. The fitting illustrated is in the form of an elbow provided with the requisite control valve 20.

To set up the machine for normal use, that is, without provision for putting in or 20 taking out steam, a full complement of diaphragms is placed in the casing and a full complement of rotors is fastened on the shaft. With all of the diaphragms in position their rims fit together and to the cylindrical bore of the casing with a steam-tight 25 joint and completely close the opening to the auxiliary low pressure chamber, as illustrated in Fig. 1, so that none of the steam flowing into the rotor and diaphragm chamber can pass to the auxiliary chamber. If it 30 is desired to take off steam or put in steam at any selected pressure stage, two of the diaphragms may be separated so as to leave a space at that stage by leaving out one or 35 more of the diaphragms and rotors. This opens a passage for steam at the desired pressure between the rotor chamber and the auxiliary chamber, as illustrated in Fig. 2, in 40 which view two diaphragms and rotors are omitted. When two diaphragms are separated they may be held in place by any suitable means for instance by blocks 21 of 45 suitable length fastened to the bridging ribs 17 in the space between the separated diaphragms. As the opening between the rotor 50 chamber and the auxiliary chamber extends the width of several diaphragms the diaphragms may be located in the casing and the rotors may be fastened on the shaft, so 55 the exposed area of the opening for the addition or withdrawal of steam may be varied in position and size according to the exigencies of the particular case, giving flexibility 60 to the turbine as far as meeting special conditions of bleeding or mixed pressure is concerned.

The auxiliary low pressure chamber may 65 be in both the upper and lower sections of the casing either with or without direct communication between the upper and lower

sections. In the form shown in Figs. 2 and 4 the lower section of the casing only has the auxiliary chamber. In the form shown in Figs. 3 and 5 both sections of the casing have an auxiliary chamber, but there is no 70 direct connection between the lower chamber 15 and the upper chamber 22 which has an opening 23 to the diaphragm and rotor chamber similar to the opening from the lower chamber. In this latter form there is 75 a T fitting 24 connected with the outlet from the lower chamber and a fitting 25 provided with a valve 26 connected with the outlet from the upper chamber, and these fittings are fastened together. In this case the lower 80 diaphragm section 27 has no nozzle while the upper diaphragm section 28 has the usual nozzles 29, also a flange 30 which extends from inside of the nozzles into contact with the diaphragm 31 outside of the nozzles on 85 the opposite side of the space. With this arrangement any quantity of steam up to the maximum flow through the turbine may be taken off from the desired stage through the lower chamber and out for use through the 90 T fitting, but should there be more steam available than is wanted for use, the excess may be returned through the valve and the upper auxiliary chamber to the next lower 95 stage of the turbine.

As a result of this invention the diaphragms and rotors may be arranged within a casing of standard form designed so that the exact operating conditions of a user may be met in the most efficient manner, for 100 the elements may be disposed either for taking out or for putting in any available quantity of steam at any desired stage. The particular number of stages in the turbine is not essential to the invention, nor is it material 105 how many or few or which of the diaphragms shall be omitted, these factors being determined by the conditions found in the plant where the turbine is to be used.

The invention claimed is:

1. A multiple stage steam turbine having a casing with a chamber containing a plurality of diaphragms and rotors, and an auxiliary chamber with an opening from the auxiliary chamber to the diaphragm and rotor chamber which opening extends the width of several of the intermediate diaphragms and rotors and may be closed by rims of diaphragms or any portion of the opening may be left exposed for the passage of steam by 115 leaving a space between diaphragms.

2. A multiple stage steam turbine having a sectional casing with a chamber containing a plurality of removable diaphragms and rotors, one section of said casing having an auxiliary chamber with an opening from the auxiliary chamber to the diaphragm and rotor chamber, which opening extends the width of several of the diaphragms and rotors and is adapted to be closed by a full 125 130

complement of diaphragms and exposed for the passage of steam by the omission of diaphragms.

3. A multiple stage steam turbine having a sectional casing with a chamber containing a plurality of removable diaphragms and rotors, said casing sections having auxiliary chambers with openings from the auxiliary chambers to the diaphragm and rotor chamber, which openings extend the width of several of the diaphragms and rotors, and are adapted to be closed by a full complement of diaphragms but exposed for the passage of steam by the omission of diaphragms.

15 4. A multiple stage steam turbine having a sectional casing with a chamber containing a plurality of removable diaphragms and rotors, said casing sections having auxiliary chambers with openings from the auxiliary chambers to the diaphragm and rotor chambers, which openings extend the width of several of the diaphragms and rotors, and are adapted to be closed by a full complement of diaphragms but exposed for the passage of steam by the omission of diaphragms, a connection between said auxiliary chambers, and a control valve in said connection.

5. A multiple stage steam turbine having a casing with a diaphragm and rotor chamber and an auxiliary chamber with an opening between said chambers, and diaphragms located in the diaphragm and rotor chamber, the rims of said diaphragms closing a portion only of said opening.

35 6. A multiple stage steam turbine having a casing with a diaphragm and rotor chamber and an auxiliary chamber with an opening between said chambers that extends the width of several of the diaphragms, diaphragms adjustably located in the diaphragm and rotor chamber with a space between two of said diaphragms over said opening, and blocks in said space and holding the separated diaphragms in place, the rims of said diaphragms closing the opening except between the separated diaphragms.

7. A multiple stage steam turbine having a sectional casing with a chamber containing a plurality of removable diaphragms and rotors, said casing sections having auxiliary chambers with openings from the auxiliary chambers to the diaphragm and rotor chamber, which openings extend the width of several of the diaphragms and rotors and are partly closed by the rims of diaphragms, and means for conducting steam received in one auxiliary chamber at one stage to the other auxiliary chamber and to the diaphragm and rotor chamber at a lower stage.

60 8. A multiple stage steam turbine having a casing with a chamber containing a plurality of removable diaphragms and rotors, and an auxiliary chamber with an opening from the auxiliary chamber to the diaphragm and rotor chamber which opening

extends the width of several of the intermediate diaphragms and rotors and may be closed by the rims of the diaphragms or any portion of the opening may be left exposed for the passage of steam by omitting dia- 70 phragms.

9. A multiple stage steam turbine having a sectional casing with a chamber containing a plurality of diaphragms and rotors, one section of said casing having an auxiliary chamber with an opening from the auxiliary chamber to the diaphragm and rotor chamber, which opening extends the width of several of the diaphragms and rotors and is adapted to be closed by a full complement 75 of diaphragms or exposed for the passage of steam by leaving a space between dia- phragms.

10. A multiple stage steam turbine having a sectional casing with a chamber containing a plurality of diaphragms and rotors, said casing sections having auxiliary chambers with openings from the auxiliary chambers to the diaphragm and rotor chambers, which openings extend the width of several 80 of the diaphragms and rotors, and are adapted to be closed by a full complement of diaphragms or exposed for the passage of steam by leaving a space between dia- phragms.

95 11. A multiple stage steam turbine having a casing with a chamber containing a plurality of diaphragms and rotors, said casing having two auxiliary chambers with openings from the auxiliary chambers to the 100 diaphragm and rotor chamber, which openings extend the width of several of the dia- phragms and rotors and are adapted to be closed by a full complement of diaphragms but exposed for the passage of steam by 105 leaving a space between diaphragms, a connection between said auxiliary chambers, and a control valve in said connection.

12. A multiple stage steam turbine having a casing with a diaphragm and rotor 110 chamber and an auxiliary chamber with an opening between said chambers, and a plurality of diaphragms located in the dia- phragm chamber with a space between two of the diaphragms, the rims of said dia- phragms closing a portion only of said opening.

115 13. A multiple stage steam turbine having a casing with a diaphragm and rotor chamber and an auxiliary chamber with an opening between said chambers that extends the width of several of the diaphragms, dia- phragms located in the diaphragm and rotor chamber with a space between two of said diaphragms over said opening, and means 120 holding the separated diaphragms in place, the rims of said diaphragms closing the opening except between the separated dia- phragms.

14. A multiple stage steam turbine hav- 130

ing a casing with a chamber containing a plurality of diaphragms and rotors, said casing having upper and lower auxiliary chambers with openings from the auxiliary chambers to the diaphragm and rotor chamber, which openings extend the width of several of the diaphragms and rotors and

are partly closed by the rims of diaphragms, and means for conducting steam received in one auxiliary chamber at one stage to the other auxiliary chamber and to the diaphragm and rotor chamber at a lower stage.
